UNITED STATES PATENT OFFICE.

FRED F. BURDICK, OF RIVER FOREST, ILLINOIS.

COLLAPSIBLE CABINET.

1,028,326.

Specification of Letters Patent. Patented June 4, 1912.

Application filed March 11, 1912. Serial No. 682,936.

To all whom it may concern:

Be it known that I, FRED F. BURDICK, a citizen of the United States, and a resident of River Forest, in the county of Cook and State of Illinois, have invented certain new and useful Improvements in Collapsible Cabinets, of which the following is a specification.

This invention relates to collapsible cabinets.

The principal objects of the invention are to obtain a collapsible cabinet for therapeutic and prophylactic purposes (principally for giving electric light baths), which is fire proof; which is easily transferred or moved from one part of a room, or chamber, to another part, or from one room to another; a device which, when collapsed, is easily crated for shipment; a device which, when collapsed, can be readily set up into operative position for use by a person seated therein or into operative position for use by a person lying on a couch therein, a device which can be changed from its position for use by a person seated to its position for use by a person lying down, and vice-versa; a device which is efficient; which will not be expensive to construct; which will be durable; not liable to get out of order; of light weight; and easily installed.

Other objects sought are disclosed in the specification and claims.

The device is made of a number of sections or panels which are joined together. One of said panels is sub-divided to obtain a two part door. The top of the device is made of several parts which are movable relative to each other so that when the panels forming the side walls are in one position an aperture is obtained through said top and when said panels are in a different position said aperture in the top is closed.

In the drawings Figure 1 is a perspective of a device embodying this invention, in operative position for use on a person seated therein. Fig. 2 is a view, looking down, of the side walls of the device (with the top removed), said walls being in the position illustrated in Fig. 1. Fig. 3 is a top plan view of the device with the several parts in the position illustrated in Fig. 1. Fig. 4 is a sectional view of the top of the device on line 4—4 of Fig. 3, viewed in the direction indicated by the arrows. Fig. 5 is a sectional view, on an enlarged scale, of a portion

of the top and side walls of the device, on line 5—5 of Fig. 4, viewed in the direction indicated by the arrows. Fig. 6 is a vertical section on line 6—6 of Fig. 3, viewed in the direction indicated by the arrows, and with a figure therein indicated by broken lines. Fig. 7 is a view of the side walls of the device in a collapsed condition ready for crating. Fig. 8 is a horizontal sectional view of one corner of the device, showing the joint between adjacent panels. Fig. 9 is an elevation of one panel and of a portion of the adjacent panel, showing the manner in which they are joined together. Fig. 10 is an elevation of a pipe or tube forming a pintle of the hinge which joins adjacent panels and also forming a base for the lamps used in the device. Fig. 11 is a top plan view with the several parts in position to use the device with a couch therein; and Fig. 12 is a vertical sectional view on line 12—12 of Fig. 11, viewed in the direction indicated by the arrows, showing a couch in elevation, and indicating by broken lines a figure on said couch. Fig. 13 is a view of a couch connection.

Similar letters refer to similar parts throughout the several figures of the drawings.

A, B, C, D, E and F, are panels forming the vertical or side walls of the device. Panel F constitutes the door of the device, and consists of parts f, and f'. One side or edge of panel F is joined by hinge G to panel E.

e is a metal rod or tube which is joined at its ends to panels A and E, to tie said panels together.

Both parts of panel F are closed when the device is in the position illustrated in Figs. 1, 2, 3 and 4; but when the device is in the position illustrated in Figs. 11 and 12 the part f' is the only one closed; and said part f' can only be closed after the person who is to receive a bath is in proper position on the couch. Part f of said panel is left open to permit the head end of the couch (P) to remain outside of the device, while the remainder is inside thereof.

The several panels A, B, C, D, E and F are made of sheet metal. Panels A, B, C, D and E are duplicates, so that a description of one is a description of all thereof. The upper edges of the sheets of metal forming the panels are turned or rolled over into a cylindrical shape, as at a. In

the cylinders or tubes thus obtained I put the electric conductors X, X, which are the ordinary covered copper wires which are used in electric lighting circuits. Portions 5 of the side edges of the metal forming the panels are cut away, and the projecting parts or lugs which are obtained thereby are rolled or turned up into cylindrical shape or form, as at a', a' and a'', a''. The 10 bottom of the sheet is rolled or turned up into cylindrical shape, as at a'''. The turning up of the cylindrical shapes at a and a''' also serves to prevent warping of the panel after it is completed.

15 H, (Fig. 10), is a pipe or tube which is provided with the holes h, h. To join adjacent panels together the cylindrical parts a'' of one panel are made to register with the like parts a' of the other panel and the 20 pipe H is then inserted in said cylindrical parts, to form the pintle of the hinge.

d are beads on the sheet metal body of the panels.

The sockets y of the electric lamps Y are 25 secured in the holes h of the pipes H, and said pipes, therefore, serve as the bases to which said lamps are attached besides constituting the pintle of the hinges which join the panels together. The electric conduct- 30 ing wires X are put into the pipes or tubes H, and are attached to the sockets y in the usual manner.

By reference to Fig. 7 it will be seen that the diameter of tube H is sufficiently large 35 to permit the folding together of the panels without removal of the lamps Y from sockets y. This constitutes one feature of my invention, and is the cause of the hereinbefore described manner of joining the 40 panels together.

When a cabinet is desired in which a person is to be subjected to the light of the lamps while seated, the several panels A, B, C, D, E and F are arranged to form the 45 sides of a heptagon, with equal angles at the junction of all the panels. When a cabinet is desired in which the person is to be subjected to the light of said lamps while lying on a couch, said panels are arranged to 50 form a rectangle two of said panels being in the same plane on each side of the rectangle, and the remaining panels forming the ends of said rectangle.

The top of the device is made of the several parts I, i, I', i', J, J', and K, K'. I'' is a recess in part I, and this recess forms an aperture for the neck of a person seated in the cabinet on stool Z. Parts J and K are pivotally connected together at L. Part J is pivotally connected to parts i at M. Part K is pivotally connected to part i at m. Part J' is pivotally connected to part K' at L'. Part J' is pivotally connected to part i at M', and part K' is pivotally connected to 65 part i at m'. When the several panels A,

B, C, D, E, and F are arranged to form a heptagon, parts J, K, and J', and K, are drawn out from the position in which they are illustrated in Fig. 11 of the drawings, into the position in which they are illustrated in Fig. 3 of the drawings. Parts J, J', are thereby withdrawn from over the recess I'' in part I. When the several parts of the top are drawn out as last above described the parts i, i', are drawn back from the position thereof which is illustrated in Figs. 11 and 12 into the position illustrated in Figs. 1 and 3. To permit part i, i', to be moved on parts I, I', respectively, the ends of said parts i, i', are turned down (to prevent longitudinal movement thereof) and said parts are laid on or under parts I, I', as preferred.

N are angle irons which are secured to the respective outside edges of the parts I, i, I', i', J, J', K, K'. The body portion of these parts is made of sheet metal. The entire top of the device is laid on the upper edges of the panels A, B, C, D, E.

P is a couch, p, p, are legs of couch P. 90 Q is netting and q, q, are braces.

R, R, are bars at the head and foot of the couch. The netting is secured to said bars R.

S, S, are springs in shell T. The shell T is provided with a slot t and the ends r of the bar R extend through and are movable in said slot. The end r of bar R abuts against one end of the spring S and the other end of said spring abuts against the end of shell T. By this construction when a person is lying on the netting Q the bars R are respectively forced against the ends of the spring S and said bar moves in slot t so far as the resiliency of springs S permits.

Part I' of the top is attached to part I. by hinges as at Fig. 3.

I claim:

1. In a collapsible cabinet vertical walls 110 consisting of panels pivotally attached together, and an additional panel pivotally attached to one of the first named panels, with rods connecting the panel which is on one side of said additional panel to the panel 115 which is on the other side thereof, said panels respectively made of sheet metal provided with lugs on the sides thereof turned into a cylindrical form, the pivots of said panels consisting of pipes or tubes, provided 120 with holes in the cylindrical walls thereof, and fitting into the cylindrically formed lugs on the sides of the panels, in combination with electric conducting wires in said pipes, and a top removably mounted on the 125 vertical walls.

2. In a collapsible cabinet vertical walls 130 consisting of panels pivotally attached together, and a two-part panel pivotally attached at one side thereof to one of the first

named panels, with rods connecting the panel which is on one side of the two-part panel to the panel which is on the other side thereof, the pivots which join said panels 5 consisting of pipes or tubes provided with holes in the cylindrical walls thereof, in combination with electric lamps, sockets to said lamps, said sockets secured in the holes in said pipes, electric conducting wires in said pipes in electric connection with said sockets, and a top.

3. A collapsible cabinet comprising vertical walls consisting of panels attached together by pivots, said panels respectively 15 made of a sheet metal body provided with lugs, said lugs and one of the ends of said body respectively turned into a cylindrical form and said pivots respectively consisting of a pipe or tube provided with holes in the 20 cylindrical wall thereof, said pipes being inserted in intermeshing cylindrically formed lugs, one of said panels arranged to form a door, rods connecting the panel which is on one side of the door panel to the 25 panel on the other side thereof, electric lamps, socket to said lamps, said sockets secured in the holes in said pipes, and electric conducting wires to the lamps, said wires disposed in the cylindrically formed upper 30 end of the panels and in said pipes, in combination with a top removably mounted on the vertical walls, said top consisting of a plurality of pieces pivotally joined together, one of said pieces provided with a recess on 35 one side thereof, with others of said pieces resting on the recessed piece and arranged to cover said recess when moved into a determined position.

5. In a collapsible cabinet, vertical walls 60 consisting of panels pivotally attached together, and an additional panel pivotally attached to one of the first named panels, with rods connecting the panel which is on one side of said additional panel to the panel 65 which is on the other side thereof, said panels respectively made of sheet metal provided with lugs on the sides, said lugs and the upper ends of the panels turned into a cylindrical form, pipes or tubes arranged to 70 form the pivots of said panels, said pipes or tubes, provided with holes in the cylindrical walls thereof, and fitting into the cylindrically formed lugs on the sides of the panels, in combination with electric lamps, 75 sockets to said lamps, said sockets secured in the holes in said pipes, electric conducting wires in said pipes, in electric connection with said sockets, and a top removably mounted on the vertical walls, said top con- 80 sisting of a plurality of pieces pivotally attached together and to oppositely placed pivotal pipes one of said top pieces provided with a recess and additional ones ar- 85 ranged to cover said recess when in a determined position.

Signed at Chicago, Illinois.

FRED F. BURDICK.
